TWO-CYCLE OPPOSED-PISTON DIESEL
ENGINE

Frederic W. Plumb, West Reading, Pa.

Application March 13, 1939, Serial No. 261,447

8 Claims. (CL 123—51)

My invention relates to internal combustion engines commonly known as Diesel engines, and more particularly to a known type of the same employing opposed pistons in a single cylinder operating on a two-cycle stroke; my main objects being to produce an engine of improved design, inherently balanced, of increased efficiency, economical operation, and of simple inexpensively manufactured units of interchangeable parts suitable for mass production and multiple assembly into power units of varying capacity.

It is recognized and accepted that better results in efficiency and economy of fuel consumption are obtained by use of a two cycle stroke with opposed pistons in one cylinder giving a 15 comparatively longer time for power expansion, and preferably in connection with water-cooled cylinders cast separately, instead of in a block of multiple cylinders; and it is an important object of my present invention to embody these 20 desirable features in a novel and improved combined cylinder-and-crank-case unit, which may be used singly, or assembled with added like units, into an engine of any desired multiple cylinders, differing from any engine heretofore known to me, and providing for true economical mass production of varyingly powered engines of great 25 simplicity and increased efficiency.

Other important objects of my invention relate to a differential action of the opposed pistons causing them to operate as valves in the control of both inlet and exhaust ports; to a simplification in the linkage of the pistons to the crank shaft and arrangement of the same to act in a single plane passing through the axis of the cylinder so as to materially reduce strains and wear on these working parts; to a unique type of mixing chamber and fuel injection nozzle of larger size than usually needed, providing for a violent state of turbulence in the cylinder-compressed air and injection of fuel charges at a lower rate of compression, to insure proper combustion; to a novel crank case compression of air acting in simple manner, without added blower or supercharger to effectively scavenger the burnt gases of combustion and supply new air for compression of the cylinders; to a novel construction of the cylinder case with an integral water jacket and fixed inlet and exhaust ports partly encircling the cylinder and with their openings into the latter inclined at angles to the cylinder axis so as to reduce friction and wear; and to the use of tubular bolts for uniting end housings, and/or a plurality of combined cylinder-and-crank-case units on a suitable multi-

ple cranked shaft, said tubular bolts also acting to convey lubricating oil to and from the crank cases.

With the above objects outlined, and with other objects that will later hereinafter appear, my invention comprises the new and improved engine construction more fully described in the following specification in connection with the drawings accompanying the same, and its novel features are particularly set forth in the appended claims.

In the drawings:

Fig. 1 is mainly a vertical sectional elevation of a cylinder-and-crank-case unit showing a preferred embodiment of my invention, the view being taken substantially on the line 1—1 of Fig. 2 in a plane passing through the axis of the cylinder, with one end closure for the cylinder case shown in section and the other in side elevation, and an added fly-wheel housing being indicated.

Fig. 2 is a transverse view taken on the line 2—2 of Fig. 1, showing the crank case in vertical cross-section, and an open end view of the cylinder case with the separate end closure therefore removed, and also indicating in cross-section a fly-wheel housing and a pump gear-case housing secured to the crank shaft; dotted lines further indicating the position of an added unit in place of the fly-wheel housing.

Fig. 3 is a plan view corresponding with Fig. 1, but shown partly in section in the plane of the cylinder axis, taken on the line 3—3 of Fig. 1.

Fig. 4 is a detail section, taken on the line 4—4 of Fig. 2, indicating the manner of connecting my unit to an end housing or an added like unit.

Figs. 5 and 6 show respectively a side and plan view of a link employed in triplicate in connecting the cylinders to the crank shaft, as seen in Fig. 1.

Figs. 7, 8 and 9 show three transverse cross-sectional views of the cylinder chamber and its surrounding jacket, being taken respectively on the lines 1—7, 8—8, and 9—9 of Fig. 1, and indicating in order the exhaust port, the mixing chamber and fuel oil injector nozzle, and the air inlet port.

Figs. 10 to 13 are diagrammatic sectional elevations corresponding with Fig. 1, indicating the cycle of piston actions: Fig. 10 showing the beginning of a power stroke; Fig. 11, the scavenging of the burnt gases; Fig. 12 the intake of fresh air; and Fig. 13 the air-compressing movement of the pistons.

Fig. 14 is a side elevation indicating an outside

view of three units fixedly united according to my invention to form a multi-cylinder engine.

In accordance with my invention each cylinder and crank case forms a separate engine unit and is designed for manufacture in single units to facilitate mass production and multiple assembly. For convenience and economy, and the use of a diversity of materials best adapted for particular needs, each unit is made up of separate interchangeable parts, 5 in the drawings indicating the open-ended cylinder case having similar separate end-closures 6 and 7, and a connected crank shaft casing preferably formed in complementary parts 9 and 10 connected in the midway plane of their shaft bearing bosses 11 and 12 in halves. The case 5 is formed with a crank case extension chamber 15 and a cylinder chamber 16 having a surrounding water jacket chamber 17 interrupted midway of its length for a mixing fuel injection passage-way 20 (Fig. 8), and spaced half encircling exhaust chamber 21 (Fig. 7), and opposite half-encircling inlet chamber 24 (Fig. 9). Chamber 21 has ports 22 communicating with cylinder chamber 16 and an outlet 23 adapted for connection to an exhaust manifold not shown. Chamber 24 has ports 25 communicating with cylinder chamber 16, and a passage-way 26 communicating with crank case extension chamber 15. Water jacket chamber 17 has inlet and outlet passage-ways 18 and 19 respectively for connection to a water cooling circulating system not shown. Ports 22 and 25 are preferably inclined to the axis of the cylinder chamber to reduce friction and wear.

Opposedly acting pistons 30 and 40 are fitted to slide longitudinally in open-ended cylinder chamber 16, and jointly act on a single crank pin 45 having a single connecting rod 46, through suitable linkage including similar rock levers 31 and 41 pivotally mounted intermediate their length at 32 and 42 respectively in suitable bearings provided in cylinder case 5, as shown, and three similar links (Figs. 5 and 6). Lever 41 has one end pivotally connected at 43 directly to the free end of connecting rod 46, and its other end pivotally connected to piston 40 through a link 44. Arm 31 has one end pivotally connected to piston 30 through link 34 and its other end pivotally connected by a link 35 to a pivotal connection 36 located midway the length of connecting arm 46.

This particular linkage connection of the pistons 30 and 40 to the single crank pin 45, has manifold advantages, of economically using numbers of quantity-producible like parts, acting as effectively as if there were two instead of one connecting rod, providing for large pivotal connections readily equipped with effective anti-friction bearings, producing a differential action of the pistons for a purpose later herein described, causing all stress and strain to act in an inherently balanced and powerfully effective straight line due to the linkage alinement in a plane, and even and uniform surface wear on pistons and cylinder walls, insuring their long service tight fitting.

The crank case and cylinder passages, as shown, are comparatively small and effectively lend themselves to practical crank case compression, thus avoiding any need of blower or supercharger for scavenging; air being drawn into said passage through ports 48 controlled by plate valves 49 (Figs. 1 and 2), formed in the top wall of each cylinder case end-closure 6 and 7, and the compressed air passing through pas-

5 sage-way 26 into chamber 24 and through ports 25 into the cylinder chamber 16. Conversely exhaust gases pass through ports 22 into chamber 21 and thence through outlet 23.

Passage-way 20 (Fig. 8) is shown as tangential to the cylinder and connects the latter to a novel mixing chamber containing a sleeve nozzle 50 and a spiral director 51, both preferably of a high heat resistant alloy metal, and fuel oil 10 is injected through a check valve 53 to a spray nozzle 52, by a pipe connection to an injection pump, not shown, the action and timing of which may be controlled by driving connection with shaft-driven gears in housing 65 (Figs. 2 and 3). The air in cylinder 16 as compressed by pistons 30 and 40 is raised to a high degree of temperature and forced into a violent state of turbulence 15 by surging into the mixing chamber and by the action of nozzle 50 and spiral director 51, and at its maximum state of compression a spray of fuel oil 20 is injected to form a combustible mixture, as well understood in Diesel engine operation. This novel type of mixing chamber and its advantageous location midway in the water jacket 17, enables me to use a larger nozzle bore than is usually considered necessary, and to inject the fuel spray charges at a lower compression ratio, 25 saving power without loss in efficiency of the combustible mixture.

The linkage connection of crank pin 45 to pistons 30 and 40 before described has a differential action on said pistons permitting use of the same for controlling the covering and uncovering of the inlet ports 25 and outlet ports 22 in timed relation to their cycles of movement. Referring now particularly to Figs. 1 and 10, which show pistons 30 and 40 at the end of their compression strokes and the crank pin 45 at its lower dead center but moving in the direction of arrow 55, pivot 38, having a shorter radius than pivot 43, swings its link 35 from a dead center alinement with crank pin 45 to an angular inclination therewith, so that piston 30 connected to link 35 through rock lever 31 and link 34 take 40 a lead in its outward power stroke movement over piston 40, due to connecting arm 46 passing through its dead center alinement with the crank shaft axis which causes a dwell in movement of rock lever 41 connected by link 44 to piston 40. This lead of piston 30 continues throughout the 45 piston power stroke so that exhaust ports 22 are uncovered before inlet ports 25 are opened. Link 35 reaches its upper dead center alinement with crank pin 45 causing piston 30 to dwell while piston 40 continues its outward movement to open inlet ports 25. The moving parts have now assumed the position shown in Fig. 11, and the incoming air acts to scavenger the exhaust gases. Connecting arm 46 again passes through its upper dead center alinement with crank shaft axis while link 35 again assumes an angular inclination with crank pin 45 so that piston 30 leads in its inward compression stroke to close exhaust ports 22 while piston 40 dwells with ports 25 open, 50 admitting a charge of fresh air to cylinder 16, as shown in Fig. 12. Fig. 13 shows both ports 22 and 25 closed and pistons 30 and 40 moving inward to their compressed position with piston 30 maintaining its lead, until they reach full compression position as shown in Figs. 1 and 10, ready to receive a fuel oil injection for the next power stroke. Air is drawn in through ports 48 in end closures 6 and 7 during each compression stroke of pistons 30 and 40 and passes into cylinder chamber 16 at the end of each power

stroke of said pistons. This timed opening and closing of the exhaust ports 22 in advance of the opening and closing of the inlet ports 25 with a joint period of both being opened to thoroughly scavenge the burnt gases, is simply and positively provided for by the above described differential action of pistons 30 and 40, which also act to compress the necessary fuel air in the crank case.

In Fig. 2 I have indicated an engine assembly according to my invention consisting of a single combined cylinder-and-crank-case unit having a fly-wheel housing 60 and a gear housing 65 connected thereto at opposite ends of the single-cranned shaft 15 shown. My combined unit has parallel side face portions of a width corresponding with the end faces of shaft bearing bosses 11-12 projecting from both sides of crank case parts 9 and 10, and the latter are provided with bolt bosses 10, 70 arranged in spaced circumferential relation, the end faces of which are also in alinement with the end faces of bosses 11-12. Fly wheel housing 60 and gear housing 65, which may be of split sections if desired, are each provided with shaft bearing bosses 61 and 66 complementary to bosses 11-12 and arranged to abut against the latter end-to-end, also bolt bosses 62 and 67 arranged to aline with bosses 10, 70 and engage against the same end-to-end. Parted clamping rings 68 or 69 are shown as fixedly uniting the respectively bosses 61 and 11-12 and 66 and 11-12 (Fig. 4). And to firmly tie said housing 60 and 65 to the crank case 9-10, bolts 71, 71 are shown engaging through the bosses 10, 70 and 62, 67. In Fig. 2, dotted lines indicate a second combined cylinder-and-crank case unit substituted for fly wheel casing 60 and united in the manner described for the latter, and any number of units may be connected together in similar manner and their end ones having housings 60 and 65 attached thereto, simply providing for ready assembly of engines of multiple cylinders, by the addition of a shaft of proper length and adequate number of cranks.

The crank shaft 15 shown in the drawings, particularly seen in Fig. 2, is formed with spaced discs 76, 77 carrying crank pin 45, and these discs are arranged to fit recesses shown formed for them in the crank case parts 9 and 10 and the sealing of the air and oil tight crank case may be secured by the use of sealing rings indicated at 18. The shaft 15 is also shown with bearing collars 29 fitted within the bearing bosses 61, 11-12 and 66, 11-12, preferably split at an angle of 180° to the split of said bearings.

To provide adequate lubricating oil to the crank case for simple splash distribution, the bolts 71, 71 are shown as formed of tubing and provided with apertures therefrom through their bosses 70, 70 leading into the crank case chamber; the upper bolt being used to furnish the oil supply, and the lower bolts to remove the used oil. End caps may be used to close said tubular bolts, and piping employed to connect them to a usual supply pump and a sump pump and filter, not shown, conveniently driven from the gears in housing 65.

It is believed the nature of my invention and its manner of operation will be readily understood from the foregoing description. It is of the simplest design, economical to manufacture, may be assembled into multiple units, occupies comparatively little space, and may be made of unusual lightness for a Diesel engine, practically

free of vibration. Its compactness, low upkeep, and economy of fuel make it adaptable for rear end automobile drive or for air plane use, as in the latter case it can be reversed and built into the wings with only the crank case exposed, thus materially reducing head resistance. It is obvious of course that the particular construction shown and above described in detail, may be modified and changed within the scope of the following claims.

What I claim is:

1. A two-cycle opposed piston engine of the compression-ignition internal-combustion type, comprising a plurality of similar interchangeable combined cylinder-and-crank-case complete engine units adapted for connected side-by-side assembly, a drive shaft having a plurality of crank pins, one for each assembled engine unit, end housing units on said shaft connected to the respective end engine units, and means for fixedly uniting said units so as to form lubricant passage-ways to the interiors of the latter.
2. A two-cycle opposed piston engine of the compression-ignition internal-combustion type, comprising a plurality of similar interchangeable combined cylinder-and-crank-case complete engine units adapted for connected side-by-side assembly, a drive shaft having a plurality of crank pins, one for each assembled engine unit, and end housing units on said shaft connected to the respective end engine units, said units having parallel abutting wall portions, and hollow tie-bolts fixedly uniting the same and forming lubricant passage-ways to the interiors of the latter.
3. A two-cycle opposed piston engine of the compression-ignition internal-combustion type, comprising a plurality of similar interchangeable combined cylinder-and-crank-case complete engine units adapted for connected side-by-side assembly, a drive shaft having a plurality of crank pins, one for each assembled engine unit, and end housing units on said shaft connected to the respective end engine units, said shaft having concentric sealing discs on each side of each crank pin, and each engine unit having internal bearing recesses adapted to receive said discs, and oil-sealing rings in the periphery of each disc.
4. A two-cycle opposed piston engine of the compression-ignition internal-combustion type, comprising a plurality of similar interchangeable combined cylinder-and-crank-case complete engine units adapted for connected side-by-side assembly, a drive shaft having a plurality of crank pins, one for each assembled engine unit, and end housing units on said shaft connected to the respective end engine units, each of said engine units having component parts of different metals forming a combined open-ended cylinder and crank case unit, and like end-closures for said unit having valved air-inlet ports and forming air-chamber extensions of said crank case.
5. A two-cycle opposed-piston engine of the compression-ignition internal-combustion type, comprising a cylinder block having an air-chambered crank casing depending midway of the length of the cylinder and arranged in communication with the open ends of the latter, oppositely moved pistons in the cylinder each provided with a pivoted crank-operating link extending into said air-chamber, a transversely mounted crank shaft in said casing having a single crank pin with an operating arm mounted thereon, and operating connections between each of said piston-pivoted links and said crank oper-

ating arm whereby the piston impulses are co-operatively transmitted to the crank shaft.

6. In a construction as set forth in claim 5, crank-operating connections to the oppositely moved pistons comprising similar fixedly-pivoted rock-arms each linked at one end to the respective pistons and having their other ends swingingly connected to said crank-pin operating arm at differently located portions thereof relative to the center of the crank-pin so as to 10 cooperatively rotate the latter substantially as described.

7. In a construction as set forth in claim 5, a cylinder having hollow walls forming a water

jacket and spaced inlet and exhaust ports, and piston connections to the crank shaft adapted to produce a differential piston movement for control of said ports, substantially as described.

8. A cooperating plurality of engine units such as specified in claim 5, each unit having its reversely moved pistons operatively connected to a common crank shaft and the parallel units having abutting bosses through which extend hollow connecting bolts forming lubricant passage-ways communicating with the respective crank casing chambers.

FREDERIC W. PLUMB.
